CLAIM

The ornamental design for a liner for a respirator mask, as shown and described.

DESCRIPTION

FIG. 1 is a front view of a liner for a respirator mask according to an embodiment, the rear view being identical thereto;

FIG. 2 is a right side view of a liner for a respirator mask of FIG. 1, the left side view being identical thereto;

FIG. 3 is a top view of a liner for a respirator mask of FIG. 1, the bottom view being identical thereto;

FIG. 4 is a front view of a liner for a respirator mask according to another embodiment, the rear view being identical thereto;

FIG. 5 is a right side view of a liner for a respirator mask of FIG. 4, the left side view being identical thereto; and,

FIG. 6 is a top view of a liner for a respirator mask of FIG. 4, the bottom view being identical thereto.

The broken lines shown in the figures depict portions of the liner for respirator mask that form no part of the claimed design.
